TARGET PIN FOR SHUFFLEBOARD

John N. Bour, Brooklyn, N. Y.

Application October 30, 1952, Serial No. 317,719

1 Claim. (Cl. 273—127)

This invention relates to a game apparatus, the primary object of the invention being to convert the usual game apparatus in the form of a shuffleboard, into a game apparatus whereby the principles of the conventional horseshoe game may be carried out on the shuffleboard.

An important object of the invention is to provide means which may be readily and easily applied to a shuffleboard, to provide the usual pins or stakes used in the game of pitching horseshoes, to a shuffleboard, in such a way that the pins or stakes will not damage the smooth surface of the usual shuffleboard or game surface.

With the foregoing and other objects in view which will appear as the description proceeds, the invention consists of certain novel details of construction and combination of parts, hereinafter more fully described and pointed out in the claim, it being understood that changes may be made in the construction and arrangement of parts without departing from the spirit of the invention as claimed.

Referring to the drawing:

Figure 1 is a plan view of a quoit which is horseshoe shaped.

Fig. 2 is an end elevational view thereof.

Fig. 3 is a perspective view illustrating a shuffleboard with the pins or stakes positioned thereon, in accordance with the invention.

Fig. 4 is a perspective view of the cue used in directing game pieces to the target pin.

Referring to the drawing in detail, a conventional shuffleboard construction is indicated by the reference character 5, the shuffleboard being of the type wherein the game pieces are slid over the surface of the shuffleboard by means of a long-handled cue.

The pin or stake forming the subject matter of the present invention, is indicated generally by the reference character 6, and embodies rods or pipe sections 7 threaded in the ends of the coupling 8, which coupling is so constructed that the rods or pipe sections 7 extend at acute angles with respect to the side edges of the playing surface bracing the device against the impact of a game piece or quoit striking the pin, to be hereinafter more fully described.

2

At the ends of the rods or pipe sections 7 are vertical pipes 9 connected to the pipes 7 by means of elbows 10, the vertical pipes 9 being of lengths to fit into sockets 11 which are embedded in the ground surface adjacent to the side edges of the shuffleboard 5 at points near the ends of the shuffleboard, as clearly shown by Fig. 3 of the drawing.

The reference character 12 indicates the pin or stake which is connected to the coupling 8 with its lower end terminating adjacent to the surface of the shuffleboard, there being provided the rubber cushioning member or foot 13 secured to the lower end of said pin or stake, to cushion the movements of the pin should the pin be struck by a quoit, in playing the game.

It will, of course, be understood that in playing the game there will be one of these pins 12 and supports at each end of the shuffleboard or playing surface.

The quoits used in playing the game are horse-shoe shaped and are indicated by the reference character 14, and are slid over the shuffleboard by means of a cue, such as indicated by Fig. 4, the cue having a head 15 which is adapted to slide over the shuffleboard surface with the curved front edge 16 of the head fitted against the curved edge 17 of the quoit.

While I have shown and described the device for use in converting an outdoor shuffleboard, into a shuffleboard for playing a game using the rules of horse-shoe pitching, it is to be understood that by placing conventional suction cups on the lower ends of the pipes 9, the pins or stakes used in playing the game may be supported for use in indoor shuffleboards.

Having thus described the invention, what is claimed is:

In a game apparatus including a horizontal game surface, a game pin support comprising a pair of horizontal laterally extended supporting pipes, a vertical game pin, said pipes converging towards said game pin and being connected to said game pin at the upper end of the game pin, a cushioning foot member secured on the lower end of said game pin and extending upwardly throughout a portion of the length of said game pin, vertical socket members positioned in the ground surface adjacent to the side edges of the game surface, and downwardly extended pipes connected to said supporting pipes at their outer ends, positioned in said socket members supporting said pipes in upright positions.
